UNITED STATES PATENT OFFICE.

CHARLES W. BECK, OF NEW YORK, N. Y., ASSIGNOR, BY MESNE ASSIGNMENTS, TO ELECTROLITE GAS LAMP COMPANY, OF NEW YORK, N. Y.

ACETYLENE-GAS GENERATOR.

SPECIFICATION forming part of Letters Patent No. 737,196, dated August 25, 1903.

Application filed January 9, 1901. Serial No. 42,585. (No model.)

To all whom it may concern:

Be it known that I, CHARLES W. BECK, of New York, county of New York, and State of New York, have invented certain new and useful Improvements in Acetylene-Generators, of which the following is a specification.

This invention relates to improvements in acetylene-generators, and refers more specifically to improvements in that type of generators wherein granulated or pulverulent carbide is fed to a generating-chamber in regulated quantities.

Among the salient objects of the present invention are to provide a generator the feed mechanism of which is not only extremely simple in construction, but is at the same time particularly free from liability to become clogged either by reason of the carbide becoming lodged therein in such manner as to interrupt or interfere with the feeding operation or by reason of the carbide slaking and adhering to the feed mechanism, this latter result being chiefly avoided by preventing access of the vapors of generation to the carbide before it is discharged from the feed-passage and by providing a construction in which a rubbing frictional engagement takes place between the valve member which controls the feed-passage and the walls of the latter; to provide a construction in which the valve member or stopper which controls the feed-passage is provided with a flexible and yielding peripheral portion which cooperates with a tapered seat surrounding the feed-opening; to provide a construction in which the valve member is operated by direct connection with a vibrating wall or diaphragm which is actuated by the gas generated, and in general to provide a simplified and improved construction and arrangement of parts in a device of the character referred to.

The invention consists in the matters hereinafter described and more particularly pointed out in the appended claims and will be readily comprehended from the following description, reference being had to the accompanying drawing, the single figure of which shows in axial vertical section a generator embodying my invention.

Referring to said drawings, 1 designates as a whole a closed receptacle, conveniently and

as shown herein in the form of an upright cylinder and comprising upper and lower members 2 and 3, respectively, separably united, as at 4, by means of any suitable union whereby a close joint may be formed. The main generator-body is shown as supported some distance above the floor by means of a suitable base, (designated as a whole 5,) provided with legs 6, which base is so constructed as to form in conjunction with the lower end wall 3' of the generator-body a lower closed chamber 7. Within the lower chamber 7 is arranged a movable diaphragm or partition 8, having its periphery secured to the side walls 65 of said chamber 7 in such manner as to completely partition the space within said chamber, the space above the diaphragm being in communication with the gas-space of the generator, as will hereinafter appear, and the 70 space below the diaphragm being in communication with the outer atmosphere through a vent 9. In order to unite the base 5 with the generator-body in such manner as to form a gas-tight union of said parts and at the same 75 time secure the periphery of the diaphragm 8, the generator-body is conveniently provided at its lower side with a circumferential flange 10, which is externally secured thereto, to receive the correspondingly-threaded rim 11 of 80 the base. Immediately below the threaded portion of the base is formed a shoulder 12, between which and the lower surface of the flange 10 the periphery of the diaphragm is clamped when the base is secured into engagement with the flange. 85

The upper member 2 of the generator-body is provided with a downwardly-converging or conical partition 13, which divides the interior of the generator-body, the space above said 90 partition constituting the carbide-hopper, while the space below said partition constitutes the generating-chamber, the lower part of which is adapted to be filled with a body of water. At the apex of the conical hopper-bottom 13 is formed a feed-aperture 14, which is controlled by means of a valve plug or member 15.

In the preferred construction illustrated the valve-plug 15 consists of a central body 100 16, provided with a radially-extending flexible and yieldable peripheral portion 17, which

is of suitable diameter to fit within the conical lower end of the hopper-bottom and completely close the feed-opening 14 therethrough. The valve-plug is so formed that it 5 cannot be drawn through the discharge-opening by a normal working gas-pressure. As shown, the rigid central portion 16 is of such a diameter that the flexible peripheral portion cannot flex sufficiently to permit the valve to 10 pass through the opening 14. Any suitable means may be employed to accomplish this which will not prevent the flexible portion of the valve being forced against the valve-seat. It is to be understood that the entire body of 15 the valve-plug may be made of suitable material to provide the flexible and yielding peripheral portion; but in the preferred construction shown herein said plug is of composite construction, comprising the rigid conical- 20 shaped central body 16, the disk 17, of soft rubber, arranged to underlie said body 16 and having its periphery extending beyond the periphery of the conical body throughout the entire circumference, and a clamp-nut 18, underlyng the rubber disk 17, all three of said parts being supported and united by means of a stem 19, with which the members 16 and 18 have screw-threaded engagement. The operating rod or stem 19 extends downwardly 25 through the generating-chamber and into the lower chamber 7, its lower end being operatively connected with the diaphragm 8 in such manner that the movement of the latter is imparted to the operating-stem to reciprocate 30 the valve-plug to and from its seat. The pressure of the gas in chamber 7 holds the valve-plug to its seat, and, as is obvious, the greater this pressure the more securely will the discharge-opening 14 be sealed to prevent the 35 passage of carbid to the generating-chamber. Should any carbid leak past the valve, the generation of gas would cause the valve to be drawn to its seat with an increasing pressure until the leak of carbid were stopped. 40

45 In the construction shown washers or confining-plates 20 21 are arranged upon opposite sides of the central portion of the diaphragm, and the end of the operating-rod has screw-threaded engagement with said plates or 50 washers, as indicated as 22.

In order that the liquid within the generating-chamber may be excluded from the lower gas-chamber 7, a sleeve 23 is secured to the bottom wall of the generating-chamber 55 concentric with the operating-rod 19 and arranged to extend upwardly to a point well above the normal liquid-level of said chamber, and in order to prevent access of carbid or residue to said sleeve the operating-stem 60 is provided at a point a short distance above the upper end of the sleeve with a conical deflector 24, which is provided at its under side with a sleeve-like extension 25, constructed to fit and telescope within the upper end of the 65 sleeve 23, said extension 25 forming a guide which operates to hold the valve-plug accu-

rately centered relatively to the feed-opening which it controls.

In order to afford a communication for the passage of gas from the upper part of the generating-chamber to the lower gas-chamber 7, that part of the operating-rod 19 below the deflector 24 is made hollow or of tubular construction and gas-ports 26 27 are formed at each end which communicate, respectively, 70 with the generating-chamber and lower gas-chamber. In order to afford a more direct passage for the gas from the generating-chamber to the inlet-ports 26 of the operating-rod, the guide-sleeve 25 is likewise provided with 80 ports 28.

29 designates a coiled expansion-spring arranged within the sleeve or housing 23, concentrically upon the valve-stem, the upper end of said spring being arranged to engage 85 the under surface of the deflector 24, so as to exert its tension upwardly upon the valve-stem, and its lower end resting in engagement with a screw-plug 30, which forms the closure of the lower end of the housing 23, through 90 which the valve-stem reciprocates. By means of this construction it will be obvious that the tendency of the spring is to force the valve-plug upwardly to open the feed-passage, while the pressure of gas generated acting upon the 95 inside of the vibrating diaphragm 8 tends to force the valve-stem downwardly and to thus close the valve. In order that the valve-stem may be locked in position to hold the valve closed, the lower end of the valve-stem is provided with a threaded extension 19', which is arranged to extend out through the vent-opening 9 and is provided with a locking-nut 30', which may be screwed up into engagement with the under surface of the base, so as to 100 hold the valve in closed position.

Preferably the gas generated in the generating-chamber is caused to pass through the upper part of the carbid-receptacle before being withdrawn from the generator in order 110 that it may be dried by passing over the extended upper surface of the body of carbid within the hopper. To this end a stand-pipe 31 is arranged to communicate at its lower end with an aperture 32, formed through the 115 conical bottom wall of the hopper, and opens at its upper end adjacent to the top wall of the generator. From the upper part of the hopper the gas is drawn off through a suitable eduction-pipe 33. Both the hopper and generating-chamber are provided with suitable filling-apertures 33' 34, respectively, each closed by a screw-plug, as 35 36.

The operation of the device, constructed as described, is as follows: Assuming that the 125 valve is in closed position and suitable quantities of carbid and water charged into the hopper and generating-chamber, respectively, the generator is brought into operation by simply screwing back the nut 30' to permit 130 the valve-plug to be forced open by the spring acting upon the valve-stem, whereupon the

carbid will begin to flow down past the yielding periphery of the valve-plug and through the feed-opening into the generator-chamber. The gas generated in the generating-chamber 5 fills the latter, and also passes down into the lower expansion-chamber, and there acts to force the diaphragm downwardly against the tension of the valve-stem spring, eventually as the pressure rises drawing the valve-plug 10 down into its tapered seat, completely shutting off the flow of carbid and effectually sealing the feed-opening. Owing to the provision of the yielding periphery upon the valve-plug and the arrangement whereby the 15 latter works into a downwardly-tapering seat, it will be obvious that the feed-opening will be closed sufficiently to shut off the flow of carbid before the movement of the valve-plug is arrested, the subsequent downward movement 20 of the valve-plug acting to compress and flex its peripheral portion into a shape conforming to the shape of the seat and at the same time causing a distinct rubbing or wiping action between the periphery of the 25 valve-plug and the seat. This feature is of great importance, since it is obvious that the stream of carbid is thereby first cut off by the extreme margin of the yielding disk, thus permitting the feed-opening to discharge and 30 empty itself before the further downward movement of the plug brings the latter into compressed engagement with the seat, so that liability of particles of carbid being trapped between the plug and its seat is reduced to a minimum. This peculiar arrangement is 35 furthermore advantageous, since it enables the valve-stem and connected gas-confining wall or diaphragm to advance a substantial distance after the flow of carbid has been interrupted, thereby providing additional room 40 for the storing of gas generated after the feed-opening has closed. A further feature of advantage incident to this construction is that the valve-plug does not open as soon as the 45 gas-bag begins to deflate, but only after the valve-stem has risen far enough to force the valve-plug a substantial distance away from its seat, so far as its main body is concerned, and far enough to carry the yielding periphery 50 of the plug out of engagement with the seat against the weight of the carbid resting thereon, and inasmuch as the carbid will tend to flex the yielding periphery downwardly as the valve-plug rises the result is that the carbid 55 is fed forward in more distinct charges as contradistinguished from a uniformly increasing and decreasing sifting-feed.

I am aware that it has heretofore been proposed to construct a carbid-feed mechanism 60 in which a tapered valve-plug co-operates with a tapered seat, one of said meeting members being covered with a rubber surfacing. Such a construction does not, however, embody my present invention for several important 65 reasons—namely, it does not afford a rubbing frictional engagement between the parts, which insures that whatever carbid or resi-

due which tends to adhere to these meeting surfaces will be wiped off, it does not afford such a flexible and yielding meeting of the 70 parts as will permit the valve to practically seal the feed-opening, even though there be adherent particles or small masses of carbid in the throat of the opening, and it does not afford any substantial further movement of the 75 valve-plug (and connected stem and gas-confining wall) after the plug first engages the seat, the rubber surfacing being supported or backed by a rigid base, which renders any substantial shaping or conforming of the meeting 80 parts to each other, as when obstructions are interposed, impossible. Moreover, in such previously devised construction the valve-plug is arranged beneath the discharge-aperture and works upwardly into a downwardly-flaring seat, and it will be obvious that in such a construction the plug will of necessity close against and into a seat filled with carbid and against the downward pressure of the body of carbid instead of first cutting 85 off the flow of carbid above and thereafter advancing downwardly into a seat or throat which is empty.

While it is obvious that a construction embodying my invention, in which the valve-plug is supported to move downwardly into its seat, possesses important advantages over a similar but reversed construction in which the valve member is moved upwardly, yet said latter construction would also possess 90 substantial advantages over the construction heretofore known, and I do not, therefore, wish to be understood as disclaiming such a construction.

The novel arrangement of the co-operating 105 parts of the generator is a feature of importance, inasmuch as it enables me to make an extremely compact and at the same time simple generator and is a construction capable of embodiment in any reasonable size—as, for example, either in a small lamp for domestic purposes or in a large generator for supplying a considerable plant with light. Moreover, the arrangement is such that ready access may be had to any part of the generator. 110

I claim as my invention—

1. In an acetylene-generator, the combination of a carbid-receptacle, provided with a discharge-opening, a downwardly-tapered converging valve-seat surrounding said discharge-opening, a valve-plug arranged to control said opening, provided with a yielding peripheral portion, a generating-chamber below said carbid-receptacle, a gas-chamber 125 below said generating-chamber, a movable gas-wall within said gas-chamber, a valve-stem operatively connected with said movable gas-wall and extending thence upwardly through the generating-chamber and operatively engaging said valve-plug, and a spring 130 arranged to act upon said valve-stem to normally force the valve-plug open, substantially as described.

2. In an acetylene-generator, the combina-

tion of a carbid - receptacle, provided with a discharge - opening, a downwardly - tapered converging valve-seat surrounding said discharge-opening, a valve-plug arranged to control said opening provided with a yielding peripheral portion, a generating-chamber below said carbid - receptacle, a gas - chamber below said generating - chamber, a movable gas - wall within said gas - chamber, a valve-
 5 stem operatively connected with said movable gas-wall and extending thence upwardly through the generating - chamber and operatively engaging said valve-plug, a housing surrounding that part of the valve-stem which
 10 extends through the generating-chamber to a point above the normal liquid - level therein and forming a well through which the valve-
 15 stem extends, a coiled expansion - spring arranged within said housing concentrically
 20 with the valve-stem and acting upon the latter to force it normally upward and a deflector surrounding the valve - stem and overlying the upper end of said housing or well, substantially as described.
 25 3. In an acetylene-generator, the combination of a carbid-receptacle, provided with a discharge - opening, a downwardly - tapered converging valve-seat surrounding said discharge-opening, a valve-plug arranged to control
 30 said opening provided with a disk-like flexible and yielding peripheral portion, a generating-chamber below said carbid-receptacle, a gas-chamber below said generating-chamber, a movable gas-wall within said gas-chamber, a valve-stem operatively connected with said movable gas - wall and extending thence upwardly through the generating-chamber and operatively engaging said valve-plug, a housing surrounding that part of the
 35 valve-stem which extends through the generating-chamber to a point above the normal liquid-level therein and forming a well through which the valve-stem extends, a coiled expansion-spring arranged within said housing concentrically with the valve-stem and acting upon the latter to force it normally upward and a deflector surrounding the valve-stem and overlying the upper end of said housing or well, and guides through which said valve-
 40 stem operates and whereby it is held centered relatively to the discharge-opening, substantially as described.
 45 4. In an acetylene-generator, the combination of a carbid-receptacle, provided with a discharge - opening, a downwardly-tapering converging valve-seat surrounding said discharge-opening, a valve-plug arranged to control said opening provided with a disk-like flexible and yielding peripheral portion, a
 50 generating-chamber below said carbid-receptacle, a gas-chamber arranged below said generating - chamber having its interior partitioned by a movable gas-wall, a valve-stem operatively connected with said movable gas-
 55 wall and extending thence upwardly through the generating-chamber and operatively engaging said valve-plug, a tubular housing sur-

rounding that portion of the valve-stem extending through the generating-chamber and rising to a point above the normal liquid-level 70 therein, a conical deflector mounted upon the valve-stem at a point above the upper end of said tubular housing and provided with a tubular guide-sleeve arranged to telescope and feed within the upper end of said housing, a gas-passage extending longitudinally through said valve-stem provided with ports opening into the space above the normal liquid-level of the generating-chamber and into the lower gas-chamber respectively, a coiled 75 expansion-spring arranged within said tubular housing and acting upon said valve-stem to normally force the latter upwardly and means for locking said valve - stem in position to hold the valve closed, substantially as 80 described.

5. In an acetylene-generator the combination of a carbid-receptacle provided with a discharge - opening, a downwardly - tapered converging valve-seat surrounding said discharge-opening, a valve-plug arranged to control said opening and provided with a yielding peripheral portion larger in diameter than the discharge-opening and adapted to conform to the tapered valve-seat under pressure, 95 and means to prevent the peripheral portion of the valve from passing into the discharge-opening, when said portion has been flexed by contact with the wall of the valve-seat, a generating-chamber below said carbid-receptacle, a gas-chamber, a movable wall forming a part of said gas-chamber, a valve-stem operatively connected with said movable wall and engaging the valve-plug whereby the gas-pressure will hold the plug to its seat, and means 100 arranged to act upon said valve-stem to normally force the valve-plug from its seat.

6. In an acetylene-generator the combination of a carbid-receptacle having a downwardly-tapered bottom wall terminating in a discharge - opening, a generating - chamber, means for controlling the feed of carbid to the generating-chamber comprising a valve member larger in diameter than the feed-opening and located above said feed-opening 110 within the carbid-chamber and provided with a yielding peripheral portion adapted to conform under pressure to the downwardly-tapered bottom wall of the generating-chamber, a rigid central part above the flexible part to 115 prevent the valve-plug passing into the discharge-opening when the flexible part has been flexed by contact with the valve-seat under normal working gas - pressure, and means operated by gas-pressure for moving 120 said valve downwardly to its seat, and means operating against the gas-pressure for raising 125 it from its seat, whereby the valve will have a rubbing contact with the converging bottom wall of the generator and will act to stop the 130 flow of carbid through the feed-opening before the valve is positively seated.

7. In an acetylene-generator, the combination of a carbid-receptacle, a generating-cham-

ber below the said receptacle, and means for controlling the feed of carbid to the generating-chamber, said means comprising a feed-passage having downward converging or tapering side wall portions forming a valve-seat, a valve larger in diameter than the feed-passage and working to and from said seat and having a flexible and yielding peripheral portion adapted to conform under pressure to said seat, means to prevent the peripheral portion of the valve from passing into the discharge-opening when said portion has been flexed by contact with the valve-seat under normal working gas-pressure, and means for opening said valve, whereby the valve will have a rubbing contact with its seat.

8. In an acetylene-generator, the combination of a carbid-receptacle, a generating-chamber below said receptacle, and means for controlling the feed of carbid to the generating-chamber said means comprising the feed-passage having downwardly-converging walls forming a valve-seat, a valve above said seat and larger in diameter than the feed-passage and working to and from said seat and having a flexible peripheral portion and a rigid central portion above the peripheral portion said rigid portion preventing the valve passing into the discharge-opening when the

peripheral portion has been flexed by contact with the valve-seat under normal working gas-pressure, and means operated by changes in gas-pressure for moving said valve to and from its seat.

9. In an acetylene-generator, the combination of a carbid-receptacle formed with a discharge-opening at its lower end, having downwardly-converging walls forming a valve-seat, a valve-plug arranged to control said opening and provided with a yielding peripheral portion and with a rigid center portion of sufficient diameter to prevent the flexible peripheral portion from passing into the discharge-opening when said portion is flexed by contact with the valve-seat under normal working gas-pressure, a generating-chamber below said carbid-receptacle, a gas-holder in communication with the generating-chamber, a valve-operating means connected to said movable wall and engaging the valve-plug whereby the gas-pressure will seat the valve, and means operating against the gas-pressure to move said valve from its seat when the gas-pressure is reduced.

CHARLES W. BECK.
